UNITED STATES PATENT OFFICE

GEORGE M. CRAWFORD, OF INGOMAR, AND JACOB M. LONDON, OF BUTLER, PENNSYLVANIA

COAL-LOADING MACHINE

Application filed June 21, 1926. Serial No. 117,246.

This invention relates to loading machines, and more particularly loading machines for use in mines, such as coal mines, where the available space is relatively limited.

In the mining of coal, or other mineral substances, in underground mines by what is known as the room and pillar system of mining, there is ordinarily provided a main heading and at regular intervals from this heading rooms are advanced laterally. When a room has been advanced to a predetermined depth, the coal between adjacent rooms is removed, the portion of the block most remote from the heading first being taken away, the retreat from the room being effected by working toward the heading. One difficulty in such a method of mining is due to the fact that the rooms must necessarily be relatively narrow, and there must be a great many posts for holding up the roof, so that it is difficult to provide for the carriage of coal from the working face in the room down to the main heading. It has been proposed to provide loading machines in the rooms by means of which the coal which has been shot down can be loaded at the working face and conveyed down to the main heading. Since the cars must be brought successively beneath the loading machine, and since there can be only one track in a room, only one car can be loaded at a time. This means that where the room has been advanced to the maximum depth of 300 feet that a single car must be pushed the whole length of the room to the loading machine, then pushed down to the main heading, and then another car must be pushed to the room to the loading machine. Consequently the maximum efficiency of the loading machine is not obtained.

Another difficulty which is encountered, with the use of present types of loading machines resides in the fact that they can not operate over a sufficient area without moving around in the room. Consequently they must be self-propelling in order to work between the end of the trackway in the room and the remote points of the working face

so that considerable time is lost in this maneuvering of the loading machine.

The present invention has for its principal object to provide a loading machine in combination with a sectional conveyor particularly arranged for cooperation therewith whereby the coal may be continuously gathered at the working face of the room and continuously conveyed to cars or other receiving means in the heading.

Another important object of the invention is to provide a loading machine of improved construction which is capable of gathering coal along an entire working face of the room so that it need not necessarily be shifted about from point to point, it being ordinarily necessary only to move the machine forward as the room advances and to move it rearward as the retreat is effected.

A further object of the invention is to provide an improvement in the general type of machine shown in Patent No. 1,445,332, dated February 13, 1923, to Jacob M. London.

The nature of the invention may be readily understood by reference to the accompanying drawings which illustrate a preferred embodiment of the invention, but we do not limit ourselves to the particular construction and arrangement of parts therein disclosed.

In the drawings:

Figure 1 is a top plan view illustrating the loader and its conveying means in operative position in a mine;

Figure 2 is an enlarged top plan view of the main portion of the machine, parts of the top cover being broken away to better illustrate the mechanism of the machine;

Figure 3 is a detail view illustrating a section taken in the plane of line III—III of Figure 2, showing a face view of one of the clutches for one of the drums of the machine;

Figure 4 is a detail view showing one of the clutch expanding wedges;

Figure 5 is a front elevation of the machine shown in Figure 2;

Figure 6 is a detail plan view of the connection between the loading arm and supporting arm of the machine;

Figure 7 is a side elevation of the supporting arm, the loading arm being shown in section, this view further illustrating the detail shown in Figure 6;

5 Figure 8 is a side elevation of the machine, the casing being shown in section;

Figure 9 is a partial transverse section in the plane of line X—X of Figure 2;

10 Figure 10 is a transverse section through the portion of the conveyer immediately back of the loading machine, this section being in the plane of line X—X of Figure 2;

Figure 11 is a detail plan view of the outer terminal of the loading arm;

15 Figure 12 is transverse section in the plane of line XII—XII of Figure 11;

Figure 13 is a side elevation of that portion of the loading arm shown in Figure 12;

20 Figure 14 is a transverse section illustrating in detail the scraper and its slidable support on the loading arm;

Figure 15 is a transverse section through one of the scrapers in the plane of line XV—XV of Figure 14;

25 Figure 16 is a side elevation of the outer terminal of the loading arm;

Figure 17 shows an extension section for the loading arm of the machine.

In the drawings, 2 designates a box-like 30 casing which preferably has a bottom plate 3, a sectional top 4, and suitably arranged side walls. The bottom plate 3 has an extension 3^a at the forward end thereof which projects well beyond the forward end of the casing or housing, and secured to this extension is a semi-circular rail section 5. Mounted to slide on the rail 5 is a shoe 6 which fits around the rail and which is best shown in Figure 7. This shoe may be releasably secured in any given position by one or more bolts 7 which may pass therethrough and pass through the web of the curved rail section 5. The shoe supports a loading arm 8 which may be of any suitable shape, but 45 which is preferably made of I-beam laid horizontally. The loading arm may be comprised of a single length of I-beam but is preferably made up of sections, such as the section 8^a shown in Figure 17, these sections being secured together by the connecting plates, such as the fish plates 9. The outer end portion of the loading arm is preferably curved, as shown in Figure 11, this outer curved terminal section being designated 8^b. 50 By using as many sections 8^a as desired, the length of the loading arm can be varied to suit all necessary conditions.

As shown in Figure 7, rollers 10 may be provided in the shoe 6 for supporting the 60 loading arm to enable it to be slid back and forth in the shoe when necessary, and to prevent such sliding movement when it is not desired, clamping bolts 11 may be provided in the shoe, these bolts having hooked ends 65 which engage under the loading arm flanges,

as shown in Figure 7. By adjustment of the nuts on the bolts 11 the loading arm can be clamped to prevent longitudinal movement thereof. In the ordinary operation of the machine the loading arm is clamped in a given position and it will only be adjusted from time to time as conditions require.

70 Connected with the shoe 6 is a vertical post 12 having a rearwardly extending portion 13 that is pivotally secured to the top of the casing at 14. This post serves as a supporting brace for the shoe and permits the shoe to be slid around on the rail 5 as required.

75 The outer terminal of the loading arm, shown in detail in Figure 11, is preferably supported on a swiveled caster 15. At intervals along its length the supporting arm may have supporting shoes thereon to prevent it from sagging. These supporting shoes are clearly shown in Figures 12 and 13 and comprise clamps slidable along one flange of the I-beam section of the arm. Depending from these clamps, designated 16, is a post 17 having a shoe 18 which is preferably convexed to facilitate its being slid over the floor of 80 the mine. These supporting elements can be clamped in position by means of an adjusting screw 19, as will be readily understood by those skilled in the art.

85 Slidable along the loading arm are one 90 or more shoes 20 which are guided on the I-beam section of the arm by one of the flanges thereof, and which are retained in place by one of the flanges of the I-beam. We have illustrated three of these shoes 20. Each of 95 these shoes carries a scraper or gathering scoop 21. The scrapers 21 are pivotally secured to the shoes 20 by the pins 22, and on the back of each shovel there is preferably provided a heel 23. As thus arranged the scrapers can swing in against the loading arm when they are moving in one direction, see for instance the dotted line position of one of the scoops in Figure 11, while the heel 23 prevents the scoops from swinging back too 100 far in the other direction. When the shoes 20 are pulled toward the machine, sliding along the loading arms, the scoops 21 engage the loose coal and the resistance of the coal 105 causes the scoops to open out to the maximum extent permitted by their respective heels. As the shoes continue to slide along the loading arm these scoops will gather coal and scrape it toward the loading machine. When 110 the shoes are pulled in a direction away from the machine, the backs of the scoops engage the coal and the scoops swing in against the loading arm so that they ride past the coal.

115 In this way they function, upon reciprocation of the shoes along the loading arm, to always scrape coal toward the loading machine. In Figure 11 we have shown the scoops as being relatively close together, but as a matter of practice they may be so distributed along the loading arm that one scoop 120 125 130

will deliver its charge of coal into the path of travel of the next succeeding scoop toward the machine, the last scoop toward the machine only taking the coal into the loading machine. As thus arranged the scoops do not need to travel such a great distance along the arm. For instance, with a loading arm 30 feet long the scoops could be distributed at regular intervals so that they would not have to travel back and forth more than 10 feet.

By having the scoops close together, as shown in Figure 11, the operator can control the movement of the scoops, letting them travel a long or short distance, as required. This has many advantages, in that loose coal close to the machine may first be loaded, and the shovels caused to progressively bring in coal more remote from the machine. The distribution of the shovels may therefore be such as to suit the particular conditions of their use. Figure 1 shows the scoops distributed.

According to the present invention, means is provided for reciprocating the scoops back and forth along the loading arm. Other means is provided for receiving the coal which is scraped to the machine by the scoops, and other means is provided for conveying the coal thus received in the machine to the main heading in the mine or to any other suitable point of discharge.

To this end we provide a motor 25 in the casing. Through a reducing gear 26 this motor drives a shaft 27. The shaft 27 is geared through a sprocket chain 28 with a second shaft 29. When the motor 25 is operating, shafts 27 and 29 are continuously driven. Loose on the shaft 27 is a drum 30 and loose on the shaft 29 is a drum 31. Each of the drums is preferably flanged, and within the flange is a disc 32 which is keyed to the shaft on which it is carried. The disc 32 is of smaller diameter than the interior of the flanged portion of the drum, and interposed between the periphery of the disc 32 and the inside of the flange of the drum is a split ring 33 which may be expanded by wedges 34. The wedges of the drum 30 are operated by a system of toggle levers 35 and the wedges for the drum 31 is operated through a system of toggle levers 36. Both systems of toggle levers 35 and 36 are connected with a double crank 37 on a vertical shaft 38. The vertical shaft 38 is adapted to receive an operating lever not shown.

By rotation of the vertical shaft 38 in opposite directions the wedges of the respective clutches can be alternately moved to operative position while the clutch of the other drum is released. By adjusting the shaft 38 in a neutral position both drums can be disengaged from their respective driving shafts.

While we have described a particular form of clutch well adapted to the limited space

available in a machine of this kind, any other suitable form of clutch could be provided for alternately connecting the drums with their respective driving shafts. It is preferable that these clutches be under the control of a single operating handle so that at no time will it be possible to have both clutches in operative position at the same time.

Reeled about the drum 30 is a cable 39 which is guided over sheave 40 and sheave 41 to another sheave 42 at the top of the post 12. The cable 39 passes down the post and over guiding sheaves 43 and 44 out along the loading arm. At the outer end of the loading arm the cable 39 passes around a guiding sheave 45 and connects to the outermost shoe 20 of the series at 46. This shoe is connected with the next adjacent shoe through a section of cable 47, and this intermediate shoe is in turn connected with the first shoe of the series through a cable section 48.

Reeled about the other drum 31 is a cable 49 which passes from a guiding sheave 50 around a pulley 51 that is supported on a stud 52 on the extension plate 3^a of the bottom of the machine. This cable 49, after passing around the pulley 51 is guided by pulleys 53 and 54 to a sheave 55 at the inner end of the arm 13. It passes from this sheave to sheave 56 at the top of the post 12 and is guided down the post and around sheaves 57 to the loading arm. It extends along the loading arm and connects at 60 with the forwardmost shoe 20 on the loading arm.

From the foregoing it will be seen that by alternately operating the clutches to alternately operate the respective drums 30 and 31, the cables 39 and 49 may be alternately driven and released to pull the series of scrapers back and forth along the loading arm, thereby providing a simple drive for reciprocating the scrapers. The cables are flexible to adjust themselves to any angle to which the loading arm is set, and permit of the ready extension or contraction of the effective length of the loading arm, as conditions may require.

On the stud 52 secured to the plate 3^a is the hub 61 of a large disc 62 which is preferably inclined forwardly to a slight extent. Secured to this hub 62 is a disc 63. The pulley 51 is concentrically supported about the disc 63 and has an internal ratchet 64 with which pawls 65 on the disc 63 cooperate.

It will thus be seen that as the cable 49 operates the pulley 51 in alternately opposite directions, the pawl and ratchet mechanism which is best shown in Figure 2 will serve to transmit a one way rotation to the disc 62.

Supported at its inner edge on the curved rail 5 is an inclined plate 66, see Figure 5. The outer edge of this plate rests on the ground. The inner edge of the plate is merely set over the rail, it having a suitable saddle 67 to set on the rail. The gathering

120

125

130

scoops scrap the coal up to the outer edge of this plate, and succeeding operation of the scoops pushes the accumulation of coal up the plate 66 on to the intermittently revolving disc 62. The coal, falling on to the disc 62 is carried around on the disc and it is discharged into the conveyer designated generally as 68. A plate 69 serves to force the coal from the disc into the conveyer.

10 The conveyer must necessarily be of a type which can be readily made up in sections and which can be extended and contracted with the advancing and retreating operations in the mine. I have illustrated in a general 15 way such a conveyer, and the conveyer per se constitutes the subject matter of our copending application, Serial No. 117,247, filed June 21st, 1926.

According to the preferred form of conveyer, there is provided a horizontal I-beam 70 which is made of sections, the length of the I-beam 70 determines the length of the section. This I-beam has secured to its bottom a plate 71, see Figure 10, and an outer 20 flange 72. Slidable on the I-beam 70 at intervals are shoes 73, and secured to these shoes is an angle bar 74. The angle bar 74 supports a plate 75 and extending out from this plate at regular intervals are flights 76. 25 These flights, as may be seen in Figure 8, are inclined in one direction and have an abrupt vertical shoulder. The inclined surface is designated 76^a and the vertical shoulder is designated 76^b. Since the shoes 73 are slid- 30 able on the stationary I-beams 70, the plate 75 with its flights 76 may be reciprocated back and forth a distance corresponding to the distance between flights. On the back stroke of the angle bar 74 the inclines will ride under the coal, and on the forward stroke the vertical shoulders 76^b will advance the coal. 35 Thus a step by step forward movement of the coal is obtained. The coal is confined between the flanges 72 and the plate 75 so that it must move forward, while the bottom plate 40 71 forms a smooth surface over which the coal can slip. It will be apparent that the conveyer as thus constructed can be readily made up in sections that may be easily bolted together, as more specifically described in our 45 copending application above referred to.

The conveyer extends forward along one side of the housing to a point immediately adjacent the point of discharge for the disc 50 63. On the shaft 29 is a drum 77. On the outer face of the drum 77 is an eccentric pin 78 and this pin connects with one end of a connecting rod 79. The other end of the connecting rod 79 is pivotally connected at 55 80 with a connecting block 81 which is slidable on the I-beam 70. This connecting block corresponds to one of the shoes 73.

From the foregoing it will be seen that with the rotation of the shaft 29 a reciprocal 60 movement of the conveyer will be obtained

by reason of the eccentric pin 78 and the connecting rod 79.

In the operation of the machine the loading arm is set to the proper angle to gather in coal from that face of the room or that working face of the mine where loading is to be effected. The arm can be entirely removed from its supporting shoe whenever this is desired and reversed, in which case the scraper shoes are entirely removed from the arm and reversed thereon. The arm can also extend from either side of the machine. When the arm is adjusted to a given angle the plate 66 can be moved around to the necessary angle to receive the coal. The loading arm is therefore capable of working along any part of a working face in any mine. In the usual practice the arm will ordinarily extend always from the same side of the machine so that the changing about of the arm is not frequently necessary. The arrangement herein provided, however, will permit of this changing about very quickly and easily. By reason of the fact that the arm is made in sections, it can be extended to the greatest extent necessary for practical purposes.

When the arm has been set to the desired position the motor 25 is operated, and the machine operator controls the operation of the drums through a lever connected with the shaft 38. By manipulation of this lever he can cause the scrapers to be rapidly moved back and forth along the loading arm. As the coal is gathered in, the angle of the arm is gradually changed so that substantially all of the coal can be collected. As the coal is scraped toward the machine it accumulates at the machine and is forced up the plate 66, falling on to the intermittently revolving disc 62. From the disc it is forced or pushed from the disc into the forward-most end of the conveyer. The conveyer is operated continuously and by reason thereof the coal is carried back along the conveyer as rapidly as it is gathered.

The drum 77 can be effectively used as a winch for pulling posts, for hauling supplies over the mine floor, and for dragging the machine about when one end of a rope attached to the drum has its other end secured to a jack or other fixed support.

Not only is the machine particularly advantageous by reason of the wide range of positions which the loading arm may operate and the rapidity with which the coal may be gathered and conveyed to the heading of a mine, or other point of discharge, but the machine can be built cheaply and ruggedly. The conveyer sections can be readily added between the machine and the next adjacent conveyer section whenever this is necessary and even more easily added by attaching them at the discharge terminal of the conveyer where there is usually plenty of available

70

75

125

130

room and then sliding the whole conveyer forwardly. All of the parts are compactly arranged so that the machine will very effectively operate in low coal, it being possible to efficiently use the machine in a seam 30 inches high. By driving the conveyer and the gathering means from a common motor, it is assured that the coal can be carried away as rapidly as it is gathered and no other power plant is necessary in the room for operating the conveyer.

Another important advantage of the machine arises from the adaptability of the machine to the operation of the retreating from a room as well as in the operation of advancing. By reason of the fact that the scoops can operate on either side of the arm, they can collect the coal on any face at any angle. This not only makes the machine extremely adaptable to ordinary room and pillar systems of mines, but enables it to be just as conveniently used with other systems, notably certain long well systems and room and pillar systems having angular or V-shaped faces.

While the machine is also particularly adaptable to a system where a machine is used with a conveyer in such manner that it will ordinarily not shift around in the mine to any considerable extent, it can be wheeled or carried on tractors in a manner common to other machines, such as that shown in our patent hereinbefore mentioned. Any features shown in our said patent, as well as the tractor attachment for the loading arm 30 shown in patent of J. M. London, No. 1,615,640, dated January 25, 1927, may be incorporated in the present machine.

In the foregoing we have described the machine in connection with a room and pillar system of mining, but it will be obvious that the use of the machine is not confined to any particular system of mining. It will also be understood that various changes and modifications may be made in the construction of the machine within the spirit of our invention and under the scope of the appended claims, the drawings merely illustrating one embodiment of our invention.

We claim:

1. A loading machine including a machine frame, a loading arm carried thereby, a scraper movable along the arm, a receiving disc for receiving material from the loading arm means, and a conveyer associated with the machine to which the receiving disc delivers.

2. Apparatus for loading materials including a machine frame, an adjustable loading arm associated therewith, a scraper movable along the arm, means on the frame for moving the scraper back and forth along the arm, a revolute receiving disc at the forward end of the machine frame, and a conveyer for receiving material from the disc.

3. A loading machine including a support-

ing frame, a loading arm adjustably carried thereon, a scraper reciprocal along the arm, means for driving the scraper, a revolving receiving disc to which the reciprocal scraper delivers, and a reciprocal conveyer associated with the machine and terminating adjacent the receiving disc.

4. A loading machine including a supporting frame, a loading arm adjustably carried thereon, a scraper reciprocal along the arm, means for driving the scraper, a revolving receiving disc to which the reciprocal scraper delivers, and a reciprocal conveyer associated with the machine and terminating adjacent the receiving disc, said reciprocating conveyer being operatively connected with the driving means for the scraper.

5. In a loading machine of the class described, a machine body, a loading arm adjustably carried thereby, a scraper slidably guided along the arm, cables for moving the scraper in opposite directions along the arm, alternately operable drums to which the said cables are connected, a rotatable receiving disc to which the scraper delivers, and a conveyer for receiving material from the receiving disc.

6. A loading machine of the class described including a machine frame, a loading arm arcuately movable about one end of the frame, a scraper reciprocal along the arm, means on the frame for operating the scraper, and a rotating disc for receiving material from the scraper.

7. A loading machine of the class described including a machine frame, an arm angularly adjustable with respect to the frame and located at the forward end thereof, a scraper movable along the arm, means on the frame for reciprocating the scraper, and a receiving disc operatively disposed at the front of the machine frame for receiving material gathered by the said scraper.

8. A loading machine of the class described including a machine frame, an arm angularly adjustable with respect to the frame and located at the forward end thereof, a scraper movable along the arm, means on the frame for reciprocating the scraper, and a receiving disc operatively disposed at the front of the machine frame for receiving material gathered by the said scraper, a conveyer terminating beneath the disc, and means for forcing material from the disc into the conveyer.

9. A loading machine of the class described including a machine frame, an arcuately adjustable supporting shoe at the forward end of the frame, a loading arm adjustably carried in the supporting shoe, a scraper movable along the loading arm, cables for operating the scraper, power driven drums on the machine frame for operating the cables, and guiding sheaves for the cables.

10. A loading machine of the class described including a machine frame, a sup-

porting member at the forward end of the frame, a loading arm slidably received in the supporting member, clamping means on the supporting member for holding the arm in adjusted position, a scraper slidable along the arm, operating means on the frame and cables connecting the operating means with the scraper.

11. A loading machine of the class described including a machine frame, a receiving disc rotatably mounted at the front of the frame, means for driving the disc, and a loading arm concentrically adjustable about the disc for delivering material thereto.

15. 12. A loading machine of the class described, a machine frame, a receiving disc at the forward end of the frame, a loading arm at the forward end of the frame, a scraper movable along the arm, and driving means on the frame for operating the disc and the scraper.

13. A loading machine including a machine frame, a receiving disc at the forward end of the frame, a supporting element arcuately adjustable about the periphery of the receiving disc, a loading arm carried by the supporting element, a reciprocal scraper on the arm, and operating means for the disc and the scraper.

30. 14. A loading machine including a machine frame, a receiving disc at the forward end of the frame, a supporting element arcuately adjustable about the periphery of the receiving disc, a loading arm carried by the supporting element, a reciprocal scraper on the arm, cables for operating the scraper, driving means for the cables, and a driving connection between one of the cables and the receiving disc for rotating the latter upon operation of the scraper.

15. A loading machine including a machine frame, a receiving disc at the forward end of the frame, a supporting element arcuately adjustable about the periphery of the receiving disc, a loading arm carried by the supporting element, a reciprocal scraper on the arm, cables for operating the scraper, driving means for the cables, and a driving connection between one of the cables and the receiving disc for rotating the latter upon operation of the scraper, and a continuously driven conveyer for receiving material from the disc.

55. 16. The combination with a loading machine having a receiving disc at its forward end and having a gathering arm with a reciprocal scraper thereon for delivering to the receiving disc, of a conveyer connected with the machine and extending rearwardly thereof, said conveyer being positioned to receive material from the disc.

60. 17. The combination with a loading machine having a receiving disc at its forward end and having a gathering arm with a reciprocal scraper thereon for delivering to the

receiving disc, of a conveyer connected with the machine and extending rearwardly thereof, the conveyer being positioned to receive material from the disc, said conveyer being in sections whereby it may be extended or constructed according to the position of the loading machine, and a common driving means for the machine and the conveyer.

70. In testimony whereof we have hereunto set our hands.

75. GEORGE M. CRAWFORD.
